The ornamental design for a light emitting diode lamp, as shown and described.

(51) **LOC (8) Cl.** **26-04**

DESCRIPTION

(52) **U.S. Cl.** **D26/2**

FIG. 1 is a perspective view of a light emitting diode lamp showing the new design.

(58) **Field of Classification Search** D26/1-4;

FIG. 2 is a front view thereof.

313/313, 315, 317, 318, 493; 315/52, 53,

FIG. 3 is a rear view thereof.

315/56, 57, 58

FIG. 4 is a left side view thereof.

See application file for complete search history.

FIG. 5 is a right side view thereof.

(56) **References Cited**

FIG. 6 is a top view thereof.
